PLASTIC JUG

Norman A. Kelly, Wayne Township, Kosciusko County,
Ind., assignor to Crystal Preforming and Packaging,
Inc., Warsaw, Ind., a corporation of Indiana

Filed Apr. 12, 1965, Ser. No. 84,738

Term of patent 14 years

The portion of the term of the patent subsequent to
Oct. 5, 1979, has been disclaimed

(Cl. D58—5)

FIGURE 1 is a perspective view of a plastic jug embodying my new design wherein the finish and closure thereof are of the screw type as shown.

FIGURE 2 is a front elevational view thereof;

FIGURE 3 is a side elevational view thereof with the cap separated therefrom;

FIGURE 4 is a top plan view;

FIGURE 5 is a rear elevational view;

FIGURE 6 is a bottom plan view;

FIGURE 7 is a perspective view of a plastic jug showing another embodiment of my design, wherein the finish and cap thereof are of the slip type as shown; and

FIGURE 8 is a side elevational view thereof with the cap separated therefrom.

I claim:

The ornamental design for a plastic jug, as shown and described.
